UNITED STATES PATENT OFFICE.

HARRY A. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

CIRCULAR-KNITTING MACHINE.

1,078,679.

Specification of Letters Patent. Patented Nov. 18, 1913.

Original application filed May 17, 1912, Serial No. 697,861. Divided and this application filed October 29, 1912. Serial No. 728,364.

To all whom it may concern:

Be it known that I, HARRY A. HOUSEMAN, a citizen of the United States, residing at Philadelphia, county of Philadelphia, and 5 State of Pennsylvania, have invented a new and useful Improvement in Circular-Knitting Machines, of which the following is a full, clear, and exact description, reference being had to the accompanying drawings, 10 which form a part of this specification.

This application is a division of an application filed by me May 17, 1912, Serial No. 697,861.

The object of the invention forming the 15 subject-matter of this application is to provide means more particularly adapted for the manufacture of half hose. In the manufacture of such hose by means of a machine of the character set forth in my said application Serial No. 697,861, the leg, heel, foot and toe are successively knitted. After the toe is completed, a number of round and round courses are knit, the machine is then stopped, the yarn is broken, the stocking 20 is pressed off the needles by turning the machine about two revolutions, and the rear bank of needles is moved out of action preparatory to leveling all the needles for the 25 transferring operation. After the transferring operation, the machine is again turned to bring the cams into operative relation with certain needles of the front bank, and the rear bank of needles is moved into operative position, and then follows the knitting 30 of the leg, the heel, the foot and the toe of another stocking.

The object of the present invention is to provide means whereby the foregoing operations may be effected. In my said application Serial No. 697,861, such means are fully 40 set forth, as well as other means adapted to the manufacture of ladies' hose.

In the present application, I have illustrated, and shall hereinafter describe, only 45 such portion of the mechanism set forth in said application Serial No. 697,861 as is employed in the manufacture of half-hose.

In the drawings: Figure 1 is a front elevation of the machine; Fig. 2 is a sectional plan on the line 2—2 of Fig. 1; Fig. 3 is a side view looking toward the left of Fig. 1; Fig. 4 is a detail side view of one of the main pattern ratchets and part of the mechanism for shifting from rotation to oscillation and vice versa; Fig. 5 is a section on the line 5—5 of Fig. 2; Fig. 6 is a partial side view looking from the right of Fig. 1; Fig. 7 is a section on the line 7—7 of Fig. 1 showing the belt-shifting mechanism; Fig. 8 is a plan view of the means for vertically moving and leveling the needle cylinder; Fig. 9 is a partial sectional elevation of the means shown in Fig. 8; Fig. 10 is a rear elevation of the machine, partly broken away; Fig. 11 is an enlarged sectional view of portion of knitting head.

a is the frame of the machine and *b* the upper bed plate. Projecting upward from the bed plate *b* is a spider *c* on which rests the non-rotatable needle cylinder *d*. The needle cylinder *d* has slots *e* extending from the inner periphery outward. These slots contain the needles *f* which are operated from needle levers *g* pivoted on the comb *h*. The comb *h* rests on the bed plate *b*. The rotatable cam cylinder *i* is located within the needle cylinder *d*. Resting on the needle cylinder *d* is the sinker head *k* having the cap *j* having cams adapted to actuate the sinkers or web-holders *l*. The above described construction is the same as that shown in Patent No. 903,190 issued to me November 10, 1908.

As is well understood, during the knitting of the leg of the stocking and during the knitting of that part of the stocking between the heel and toe (which I shall call the foot) the cam cylinder is continuously rotating and all the needles are in action and in the position shown in Fig. 11. During the knitting of the heel and toe, the cam cylinder is oscillated and the needles extending throughout one-half the circumference of the needle bed (hereinafter referred to as the rear bank of needles) are initially thrown out of action, which is effected by moving down a half-ring *m* engaging the tails of the needle levers corresponding to said needles, whereby said needles are swung outward and out of operative engagement with the knitting cams. During the oscillation of the cam cylinder, the needles extending throughout the remaining semi-circumference of the needle bed (that is, the front bank of needles) are thrown out of action one at a time, first at one end of the semi-circumference and then at the other end, and so on alternately until a limited number of

needles in the central part of the semi-circumference are in action; the needles are then thrown into action one at a time in approximately the reverse order in which they are thrown out. This operation is effected, in a manner known in the art, by means of two fashioning rack-plates δ actuated by two double pawls p carried by two arms s projecting from an oscillating ring r .

- 10 The shaft of the cam cylinder i from rotation to reciprocation, the depression of the half-ring m for throwing half the needles out of operative connection with the knitting cams, and the imparting of oscillating motion to the ring r , for throwing certain of the remaining needles, one at a time, into and out of operative connection with the knitting cams, are effected at the same time by means to be hereinafter described.
- 15 It will be understood that the cam cylinder i and sinker cap j are rotated and oscillated together. The cam cylinder at its lower part has on its outer face a gear 11 engaging the outer gear 13 of a ring 12.
- 20 The ring 12 carries also an inner gear 14 which engages a pinion 15 on the shaft 16. The shaft 16 also carries a pinion 17 which engages a gear 18 on the sinker head k .
- 25 The ring 12 is the driving element of the chain of gearing described. As shown, the ratio between gears 11 and 13 is one to one, between pinion 15 and gear 14 one to two, and between gear 17 and gear 18 one to two, and the cam cylinder and sinker head therefore have imparted to them precisely similar movements, as if they were rigidly secured together.

The ring 12, from which both the cam cylinder i and the sinker cap j derive their movements as described, is driven from the clutch shaft 20 in any convenient way, as, for example, by the slip clutch arrangement shown and described in my said application Serial No. 697,861.

- 40 On the clutch shaft 20 are slidably mounted the two pinions 21 and 22, which have sleeves to which are yoked the vertically movable arms 24, 24, which are moved up or down in unison as hereinafter described.
- 45 The clutch 23 is fixed on the shaft 20, between pinions 21 and 22. The upper pinion 21 is constantly rotated and the lower pinion 22 constantly oscillated. When the arms 24 are moved down, thus engaging the rotary pinion 21 with the clutch 23 and disengaging the oscillatory pinion 22, the ring 12 is continuously rotated, thus rotating the cam cylinder i and sinker cap j . When the arms 24 are elevated, thus disengaging the rotary pinion 21 from the clutch 23 and engaging the oscillatory pinion 22, the ring 12 is constantly oscillated, thus oscillating the cam cylinder i and sinker cap j .

The pinion 21 is constantly rotated by means of a spur gear 25 meshing with the

pinion 21. The shaft 26 of the spur gear 25 also carries a bevel gear 27 driven from a bevel pinion 28 on the driving shaft t .

The pinion 22 is constantly oscillated by the following means: On the shaft 26 is a crank 29 connected by a link 30 with an arm 31 turning on a post 32. Extending from the hub of the arm 31 is a quadrant 33 engaging the pinion 22.

The mechanism for vertically moving the arms 24, and thereby changing from rotation to oscillation, and vice versa, will now be described. These arms are secured to a post 60 (see Figs. 2, 4 and 5). The post 60 has a pair of collars 61 between which extend the forked ends of a lever 62 pivoted between its ends on the frame of the machine. The lever is actuated by means of a double cam 63, 64 secured to a sleeve 67 on the shaft 69 (see Figs. 4 and 10). These cams rotate together and may be integral one with another. Each cam has a high part and a low part. The high part of cam 63 is adapted to coact with an arm 65 on the lever 62. The high part of cam 64 is adapted to coact with an arm 66 on the lever 62. When the high part of cam 63 coacts with the arm 65, the post-engaging end of the lever 62 is moved and held down, thereby moving down the post 60, the arms 24 and the pinions 21 and 22, thereby clutching pinion 21 with the clutch 23 and dictating the rotation of the cam cylinder i and sinker cap j . When the high part of cam 64 coacts with the arm 66, the post engaging end of the lever 62 is moved and held up, thereby dictating the oscillation of the cam cylinder i and sinker cap j . The length of the high part of each cam 63 and 64 corresponds with the length of the low part of the other cam, and the arrangement is such that when the high part of one cam starts to ride under its corresponding lever arm, the high part of the other cam starts to recede from its corresponding lever arm. Thus the lever 62 is always in positive engagement with one cam or the other.

The double cam 63, 64, is caused to turn by means of a pattern ratchet wheel 68, also secured to the sleeve 67, which ratchet wheel is turned initially by first turning the sleeve 67 and then by means of a pawl 70.

The following means are provided for initially turning the sleeve 67: u is the pattern chain, the same extending around sprocket wheels 71 and 72, the former being driven by means to be hereinafter described. Just before it is desired to change from rotation to oscillation, one of the lugs v on the pattern chain engages a cam lever 73, pivoted on the machine frame, and rocks the same. The cam lever 73 is connected, by means of a link 74, with a lever 75 pivoted on the cam shaft 77. The lever 75 carries a pawl 76 adapted when actuated from the cam lever 130

73 through the medium of link 74 and lever 75, to engage a single-toothed ratchet 770 on the cam shaft 77 and thereby turn the same. The cam shaft 77 is geared to the sleeve 67 by means of the intermeshing pinions 78 and 79, and thereby the sleeve 67, together with the double cam 63, 64 and the ratchet wheel 68, are turned. The pawl 70 is constantly reciprocated, by means to be hereinafter described. By reference to Fig. 4 it will be noticed that the ratchet wheel 68 has a number of teeth (seven are shown) of which one, 80, is substantially longer than the others. During oscillation of the cam cylinder, the 15 pawl 70 plays upon the long tooth, its extent of movement being insufficient to cause it to drop back of the same. Consequently, it is inoperative to turn the ratchet wheel 68. But after the ratchet wheel 68 has been 20 turned by the pattern chain, through the mechanism just described, the long tooth is advanced to such position that on the next reciprocation of the pawl 70 it drops back of the long tooth 80 and proceeds to turn the 25 ratchet-wheel, together with the double cam 63, 64.

As the pawl 70 engages and pushes the second tooth of the ratchet 68, the high part of cam 63 recedes from the lever arm 65 and the high part of cam 64 engages lever arm 66, thereby lifting the post-engaging end of lever 62, clutching the lower or oscillatory pinion 22 to the clutch shaft 20 and unclutching the rotary pinion 21, and causing the cam cylinder *i* and sinker cap *j* to oscillate.

The constant reciprocation of the pawl 70 is effected by securing to the hub of lever 31 a section of a bevel pinion 81 which drives 45 a similar pinion 82 on the shaft 69. To this shaft is secured a holder 83 carrying the pawl 70.

On the shaft 69 is a crank pin 85, connected, by means of a link 86, with a lever 45 87 pivoted on the shaft 88 of the sprocket wheel 71. This lever 87 carries a pawl 89 which engages a ratchet wheel 90 on the shaft 88. As before described, the shaft 69 is constantly oscillated from the lever 31 by 50 means of pinions 81 and 82; and by means of the link 86, lever 87 and pawl 89, the ratchet wheel 90 is turned and the sprocket chain advanced.

At the same time the machine is shifted 55 from rotation to oscillation, it becomes necessary, as hereinbefore described, to throw out of action the rear bank of needles, which, as stated, is effected by moving down the half-ring *m* engaging the tails of the needle levers *g*, corresponding to said needles, whereby said needles are swung outward and out of operative engagement with the knitting cams. The half-ring *m* is secured to a cross-bar 92 carried by an upright rod 60 93. The rod 93 is carried by one end of a

lever 94, which is bifurcated between its ends and pivoted, at its bifurcated portion, on the machine frame. The other forked end of lever 94 embraces a stud 95, being confined between a head fixed on the top of the stud and a sleeve 97 loose on the stud, said sleeve forming the end of an arm 96 on the lower end of the post 60. On the lower end of the stud 95 is a head 98, between which and the sleeve 97 is confined a 75 coil spring 99.

When the post 60 is raised, as it is in shifting from rotation to oscillation, the sleeve 97 is raised with it, thereby lifting the forked end of lever 94 and lowering the 80 other end of the lever, thereby pulling down the rod 93, bar 92 and half-ring *m* and rendering inoperative the rear bank of needles. When the post 60 is lowered, as it is in shifting from oscillation to rotation, the sleeve 97, acting against spring 99, pushes down the stud 95 and the forked end of lever 94, thereby elevating the half-ring 85 and rendering the rear bank of needles again operative.

As soon as the machine is shifted from rotation to oscillation and the rear bank of needles is thrown out of action, it becomes necessary to oscillate the ring *r* which, as before described, actuates the fashioning 95 rack-plates *o* through the medium of the arms *s* and the double pawls *p*. The means for oscillating the ring *r* is not shown, as it has no necessary relation to the invention herein claimed.

I have now described the means for changing from rotation to oscillation and for simultaneously rendering operative the means for shifting the rear bank of needles out of action. As before stated, this occurs at the beginning of the knitting of the heel and at the beginning of the knitting of the toe. During the knitting of the heel and toe it is desirable to decrease the tension on the thread so as to permit of the insertion of an 105 extra reinforcing thread, as hereinbefore described. When said extra thread is introduced and said shift from rotation to reciprocation occurs, certain mechanism, which I will now proceed to describe, operates to lift 110 the needle cylinder and the sinker head resting thereon; thereby, as is well understood in the art, decreasing the tension on the thread.

Threaded in the spider *c* are screws 110 120 (see Figs. 8 and 9) carrying pinions 111 meshing with an internal rack or gear 112, resting on the spider *c*. Supported on the axles of the pinions 111 are parts 113 secured to the needle cylinder. By imparting 125 a rotary movement to the gear 112, the screws 110 are rotated, thereby moving the needle cylinder vertically. By this means a very fine and certain adjustment of the vertical position of the needle cylinder is se- 130

cured. Further, by lifting gear 112 out of engagement with the screws, any one of them can be independently turned a distance of one or more pinion teeth. This is of ⁵ special advantage in case the needle cylinder should not be absolutely level, as it can be leveled perfectly by independently adjusting one or more of the screws.

The gear 112 is turned at the proper time ¹⁰ automatically by means of the following mechanism (see also Figs. 3 and 8). Secured to the gear 112 is a bracket 114 to which is pivoted a rod 115 slidable in a bearing in the standard 120, on the upper bed ¹⁵ plate *b*. Secured to the rod 115 is an adjustable piece 116 carrying a screw 118 whose axis is parallel to the axis of the rod 115. The upper end of one arm of a three-armed lever 121 extends back of the screw ²⁰ 118. Another arm of the lever 121 is in line of travel of a cam 122 on the shaft 77. As before described the cam shaft 77 is given a preliminary turn in order to give a preliminary turn to the ratchet wheel 68 to ²⁵ bring it into operative relation with the pawl 70. During the time that the ratchet wheel 68 and cam shaft 77 are being turned to shift from rotation to oscillation as before described, the cam 122 underrides the lever 121 and causes it to engage and push the screw ³⁰ 118 and rod 115, thereby turning the gear 112 and lifting the needle cylinder.

The extent to which the needle cylinder will lift may be governed by adjusting the ³⁵ piece 116 on the rod 115, or more conveniently and accurately, by turning the screw 118.

The extent to which the needle cylinder may be depressed is governed by a screw ⁴⁰ 220 against which an abutment 221, secured to the gear 112, is adapted to strike on the return movement of the gear 112. The screw 220 is adjustable in a bracket 222 secured to the spider *c*. A spring pressed ⁴⁵ tent 223 engages the grooved head of the screw and holds the screw in its adjusted position.

So long as the pawl 70 is in operative relation with the ratchet wheel 68, the ratchet ⁵⁰ wheel will turn a distance of one tooth at each four rotations of the driving shaft. As continued rotation of the ratchet wheel 68 will dictate the shifting from oscillation to rotation it is necessary to provide mechanism to hold the ratchet wheel 68 stationary ⁵⁵ until the heel or toe is completed and it is desired to return to circular knitting. This mechanism is not, however, directly related to the invention herein claimed, and is not ⁶⁰ therefore herein shown and described, but reference is made to my said application Serial No. 697,861 for a full disclosure of mechanism performing this function. It may be stated, however, that this mechanism ⁶⁵ is controlled by the fashioning rack

plates *o* and is arranged to withdraw the pawl from action when it has turned the ratchet wheel 68 two more teeth, that the pawl 70 remains in its inoperative position throughout the knitting of the heel and of ⁷⁰ the toe, and that when the heel or toe is completed, the fashioning rack plates *o* permit the pawl 70 to drop back into operative position. The pawl immediately turns the ratchet wheel 68 another tooth, thereby effecting simultaneously the following operations: In the first place, the high point of cam 63 rides under the arm 65 of lever 62 and at the same time the high point of cam 64 recedes from the arm 66 of lever 62, thereby moving down the post 60, arms 24 and pinions 21 and 22, and clutching the rotary pinion 21 with the clutch shaft 20, causing the cam cylinder *i* and sinker cap *j* to rotate. In the next place, the depression of post 60 rocks the lever 94, causing it to raise the rod ⁷⁵ 93, bar 92 and half-ring *m*, thus again rendering operative the rear bank of needles. In the next place, the cam 122 rides from under the lever 121, thereby allowing the rod 115 to be returned to its original position by means of the spring 123, thereby turning the gear 112 and screws 110 to lower the ⁸⁰ needle cylinder. ⁹⁰

The above described series of operations ⁹⁵ occurs after the knitting of both the heel and toe. In the knitting of ladies' hose after the completion of the toe, the machine at once proceeds to knit the leg, first knitting the "garter top," in which a reinforcing ¹⁰⁰ thread is used, then knitting a certain length of fabric below the garter top of maximum width, but without the reinforcing thread, then gradually decreasing the diameter of the fabric, and then knitting the ankle or ¹⁰⁵ lower and narrower portion of the leg. In my said application Serial No. 697,861, mechanism for effecting this operation, without stoppage of the machine, is described and illustrated, but this mechanism ¹¹⁰ would be inoperative in the knitting of half-hose, and it is not therefore herein shown or described.

In knitting half-hose, after the toe is completed, a number of round-and-round courses ¹¹⁵ are knit. The machine is then stopped, preparatory to certain operations, well known in the art, to which I shall refer hereinafter. I will first describe the means for automatically stopping the machine. (See Figs. 1 ¹²⁰ and 7.)

On the driving shaft *t* are the fixed driving pulley 40 and the loose idle pulley 41. ¹²⁵ 42 is a belt-shifter secured to the slidable shaft 43. A spring 44 tends to move the shaft 43 into position to cause the belt shifter 42 to move the belt into engagement with the loose pulley 41. By means of a hand lever 45 engaging a collar 46 on the shaft 43, the shaft 43 and belt-shifter 42 may be ¹³⁰ 330

5 moved into position to bring the belt into engagement with the driving pulley 40, the shaft 43 being retained in this position by means of a latch 48 (on the collar 46) dropping back of a lug 49 on a bell-crank lever 50. When the lever 50 is moved into position to cause the lug 49 to recede from the latch 48, the spring 44 moves the belt-shifter 42 into position to shift the belt from the 10 driving pulley 40 to the loose pulley 41, thereby stopping the machine.

10 The actuation of the lever 50 is effected by means of a lever 160 (see Fig. 7) which is in turn actuated by a cam-wheel 161. This 15 cam-wheel is on a shaft 162, which also carries the ratchet wheel 163. On the main driving shaft *t* is a spur gear 166, meshing with a spur gear 167 (see Fig. 6). A link 168 connects a crank pin on gear 167 with 20 the outer end of the arm 165 at which point is carried a pawl 170. The arm 165 is loosely pivoted on shaft 162. The pawl 170 engages the teeth of the ratchet wheel 163. These teeth extend all the way around the 25 periphery of the wheel 163 except for a blank space somewhat shorter in length than the space occupied by three teeth. Mechanism is provided (as hereinafter described) whereby after the knitting of the toe is completed, the ratchet wheel 163 is turned to bring the first tooth of the wheel into operative relation with the pawl. Thereafter the ratchet wheel 163 will be turned a distance of one tooth at each revolution of the 30 driving shaft. After the ratchet wheel 163 is turned any predetermined number of teeth, the cam wheel 161 actuates the lever 160, which in turn rocks the lever 50, thereby permitting the spring 44 to move the belt-shifter 42 to shift the belt from the driving 35 pulley to the loose pulley. If there are any additional teeth on the ratchet wheel 163, the latter, after the machine is re-started, continues to turn until the pawl 170 has actuated the last tooth, when it proceeds to play idly on the untoothed portion of the 40 periphery of the wheel.

45 The ratchet wheel 163 is subsequently turned to bring the pawl 170 again into operative relation with the ratchet wheel by the following means: On the shaft 77 is a cam wheel 171. A bell-crank lever 172 is pivoted on the machine frame, one arm of the lever being held in contact with the cam 50 face of the wheel 171 by a spring 173 and the other arm of the lever being connected to the upper end of a link 174, the lower end of this link having a pin and slot connection with the intermediate part of a lever 175. This lever is pivoted at one end on the 55 machine frame and at the other end has a projection in line of travel of a lug 176 on the ratchet wheel 163. On the link 174 is a fixed pawl 177 adapted to engage the ratchet 60 wheel 163. A spring 178, extending between

projections on the lever 175 and link 174, maintains the pawl 177 in engagement with the teeth of the wheel 163.

Just before the first shift from oscillation to rotation (which occurs in passing 70 from the heel to the foot) the cam wheel 171 (which is provided with two high points, the second being higher than the first) engages the lever 172. As the lever 172 rides upon the first high point of the cam wheel 75 171, the link 174 is depressed. In shifting from oscillation to rotation, the cam wheel 171 is turned still farther and the lever 172 rides over the highest point of the cam. The ratchet wheel 163 is thus turned by the 80 pawl 177 but not a sufficient distance to bring the pawl 170 into operative relation with the first tooth of the ratchet wheel.

During the knitting of the foot and toe the parts described remain in inoperative 85 position, but on the shift from oscillation to rotation at the beginning of circular knitting, the cam wheel 171 again acts upon the lever 172 and link 174 as before described, and at this time the ratchet wheel 163 is advanced a sufficient distance to bring the pawl 90 170 into operative relation with the ratchet wheel 163, whereupon the operation of the latter proceeds as before described until the machine is stopped.

After the machine is stopped, the yarn is broken by hand and the stocking is pressed off the needles by turning the machine about two revolutions. It is then necessary to move down the half ring *m* to move the rear 100 bank of needles out of action preparatory to leveling all the needles for the transferring operation. I have provided the following means for then moving down the half ring *m*.

105 On the shaft 162 of the ratchet wheel 163 is a cam 180 (see Figs. 2 and 5). On the lever 94 is a lug 181 carrying an adjusting screw in line of travel of the cam 180. After the stocking is pressed off the needles as before stated, the machine is turned by hand until the ratchet wheel 163 is advanced into such position that the cam 180 will underride the screw on lug 181, thereby lifting the corresponding end of the lever 94 against the 110 action of spring 99, pulling down the other end of the lever and thereby, through rod 93 and bar 92, pulling down the half-ring *m* and moving the rear bank of needles out of 115 operative relation with the cam on the cylinder *i*. The machine is then given a partial turn to bring the cams of the cam cylinder opposite the needles that have thus been moved out of action; thereby leveling all the needles, as before mentioned. The transferring operation then proceeds, this operation, however, having nothing to do with my present invention. After the transferring operation, the machine is again turned to 120 bring the cams into operative relation with 125

130

certain needles of the front bank. Immediately thereafter the cam 180 passes beyond the screw of lug 181 and the spring 99 acts to pull down the stud 95 and the forked end of lever 94, thereby again raising the half-ring *m*, thus restoring the rear bank of needles to operative position. At this time the lug 176 has advanced to a position just behind the hooked end of the lever 175. 10 Consequently, there is no danger, due to the action of the spring 99, of the cam 180, shaft 162 and ratchet 163, being kicked forward. Further turning of the shaft 162 causes the cam 180 to engage an arm 184 on a shaft 185. 15 This shaft carries another arm 186 (see Fig. 3), which extends between two collars 187, on a rod 188, the latter being attached to one arm of the three armed lever 121. The rocking of the shaft 185 by means of the cam 20 180 causes the arm 186 to strike the lower collar on the rod 188, thereby swinging the lever 121 against the screw 118, pushing forward the rod 115, turning the gear 112 and screws 110 and thereby lifting the needle 25 cylinder to its maximum height. The needle cylinder remains in its elevated position during the knitting of only one course, as the cam 180 immediately recedes from the arm 184. Thus a single loose course is knit at 30 the top of the leg.

While in the foregoing description I have spoken of the cam cylinder as rotatable and of the needle cylinder as vertically adjustable, in accordance with the embodiment of 35 the invention shown in the drawings, I do not intend to restrict the application of my invention to this particular type of machine to the exclusion of any well known equivalent arrangement, as that in which the needle cylinder is rotatable, and the cam cylinder vertically adjustable.

Having now fully described my invention, what I claim and desire to protect by Letters Patent is:

45 1. In a circular knitting machine, the combination with the cam cylinder and needle cylinder, of driving connections to one of the cylinders, rotary mechanism and oscillatory mechanism, control mechanism, shifting means governed by the control mechanism to connect the driving connections alternately with the rotary mechanism and oscillatory mechanism, pawl and ratchet mechanism, means actuated by the control mechanism to 50 place the pawl and ratchet mechanism into operative relation with the driving shaft, means actuated by the driving shaft to operate the rotary mechanism and oscillatory mechanism, the control mechanism and the 55 pawl and ratchet mechanism, mechanism to stop the rotation of the driving shaft, and means controlled by the pawl and ratchet mechanism to operate the stop mechanism.

60 2. In a circular knitting machine, the combination with the cam cylinder and

needle cylinder, of driving connections to one of the cylinders, rotary mechanism and oscillatory mechanism, control mechanism, shifting means governed by the control mechanism to connect the driving connections alternately with the rotary mechanism and oscillatory mechanism, pawl and ratchet mechanism, means actuated by the control mechanism to place the pawl and ratchet mechanism into operative relation with the driving shaft, means actuated by the driving shaft to operate the rotary mechanism and oscillatory mechanism, the control mechanism and the pawl and ratchet mechanism, mechanism to stop the rotation of the driving shaft, means controlled by the pawl and ratchet mechanism to operate the stop mechanism, mechanism to move certain needles out of operative relation with the cam cylinder, and means actuated by the pawl and ratchet mechanism to operate said needle actuating mechanism. 70

3. In a circular knitting machine, the combination with the cam cylinder and needle cylinder, of driving connections to one of the cylinders, rotary mechanism and oscillatory mechanism, control mechanism, shifting means governed by the control mechanism to connect the driving connections alternately with the rotary mechanism and oscillatory mechanism, pawl and ratchet mechanism, means actuated by the control mechanism to place the pawl and ratchet mechanism into operative relation with the driving shaft, means actuated by the driving shaft to operate the rotary mechanism and oscillatory mechanism, the control mechanism and the pawl and ratchet mechanism, mechanism to stop the rotation of the driving shaft, mechanism actuated by the shifting means to move certain needles out of operative relation with the cam cylinder, and means actuated by the pawl and ratchet mechanism to operate the needle actuating mechanism independently, whereby the pawl and ratchet mechanism may be operated from the driving shaft, after a given shift from oscillation to rotation, to effect the automatic stoppage of the machine after a predetermined number of courses of circular knitting and permit the leveling of the needles. 90

4. In a circular knitting machine, the combination with the cam cylinder and needle cylinder, of driving connections to one of the cylinders, control mechanism, rotary mechanism and oscillatory mechanism, shifting means governed by the control mechanism to connect the driving connections alternately with the rotary mechanism and oscillatory mechanism, a ratchet having a number of teeth, a pawl adapted to actuate the ratchet when the latter is turned into a certain position, a driving shaft, means actuated thereby to operate the rotary and 125 oscillatory mechanism, the control mechanism to connect the driving connections alternately with the rotary mechanism and oscillatory mechanism, a ratchet having a number of teeth, a pawl adapted to actuate the ratchet when the latter is turned into a certain position, a driving shaft, means actuated thereby to operate the rotary and 130 oscillatory mechanism, the control mechanism to connect the driving connections alternately with the rotary mechanism and oscillatory mechanism, a ratchet having a number of teeth, a pawl adapted to actuate the ratchet when the latter is turned into a certain position, a driving shaft, means actuated thereby to operate the rotary and

oscillatory mechanism, the control mechanism and the pawl, means actuated by the control mechanism to turn the ratchet into operative relation with the pawl, mechanism to stop the rotation of the driving shaft, means controlled by the ratchet wheel to operate the stop mechanism, mechanism actuated by the shifting means to move certain needles out of operative relation with the cam cylinder, and means turning with the ratchet to operate the last named mechanism independently, whereby the ratchet may be brought into operative relation with the pawl after a given shift from oscillation to rotation, the machine automatically stopped after a predetermined number of courses of circular knitting, and the needles then automatically leveled.

5. In a circular knitting machine, the combination with the cam cylinder and the needle cylinder, of driving connections to one of the cylinders, rotary mechanism and oscillatory mechanism, control mechanism, shifting means governed by the control mechanism to connect the driving connections alternately with the rotary mechanism and oscillatory mechanism, an arm carried by the shifting means, a stud movable in said arm, a lever connected with the stud, a spring between the stud and the arm, means connected with and operated by the lever to move certain needles out of operative relation with the cam cylinder, a driving shaft, means actuated by the driving shaft to operate the rotary mechanism and oscillatory mechanism and the control mechanism, mechanism independent of the shifting means to operate the lever, connections between the driving shaft and the last named mechanism adapted to operate the lever, and means actuated by the control mechanism to render said connections operative.

6. In a circular knitting machine, the combination with the cam cylinder and the needle cylinder, of driving connections to one of the cylinders, rotary mechanism and oscillatory mechanism, control mechanism, shifting means governed by the control mechanism to connect the driving connections alternately with the rotary mechanism and oscillatory mechanism, an arm carried by the shifting means, a stud movable in said arm, a lever connected with the stud, a spring between the stud and the arm, means connected with and operated by the lever to move certain needles out of operative relation with the cam cylinder, a driving shaft, pawl and ratchet mechanism, means actuated by the control mechanism to place the pawl and ratchet mechanism into operative relation with the driving shaft, means actuated by the driving shaft to operate the rotary mechanism and oscillatory mechanism, the control mechanism and the pawl and ratchet mechanism, mechanism to stop the

rotation of the driving shaft, means controlled by the pawl and ratchet mechanism to operate the stop mechanism, and means controlled by the pawl and ratchet mechanism to operate said lever.

7. In a circular knitting machine, the combination with the cam cylinder and needle cylinder, of driving connections to one of the cylinders, rotary mechanism and oscillatory mechanism, control mechanism, shifting means governed by the control mechanism to connect the driving connections alternately with the rotary mechanism and oscillatory mechanism, an arm carried by the shifting means, a stud movable in said arm, a lever connected with the stud, a spring between the stud and the arm, means connected with and operated by the lever to move certain needles out of operative relation with the cam cylinder, a ratchet having a number of teeth, a pawl adapted to actuate the ratchet after the latter has been turned into a given position, a driving shaft, means actuated thereby to operate the rotary mechanism and oscillatory mechanism, the control mechanism and the pawl, means actuated by the control mechanism to turn the ratchet into operative relation with the pawl, mechanism to stop the rotation of the driving shaft, means controlled by the ratchet wheel to operate the stop mechanism, a cam, turning with the ratchet wheel, adapted to lift said lever, a lug turning with the ratchet and a stop carried by said ratchet-actuating means adapted to be engaged by said lug and preventing forward movement of the ratchet after the cam recedes from the lever.

8. In a circular knitting machine, the combination with the cam cylinder and needle cylinder, of driving connections to one of the cylinders, control mechanism, rotary mechanism and oscillatory mechanism, shifting means governed by the control mechanism to connect the driving connections alternately with the rotary mechanism and oscillatory mechanism, a ratchet having a number of teeth, a pawl adapted to actuate the ratchet when the latter is turned into a certain position, a driving shaft, means actuated thereby to operate the rotary and oscillatory mechanism, the control mechanism and the pawl, means actuated by the control mechanism to turn the ratchet into operative relation with the pawl, mechanism to stop the rotation of the driving shaft, a lever normally locking the stop mechanism from operation, a cam on the ratchet shaft, and a lever operable by said cam and adapted to operate the first lever to cause it to unlock the stop mechanism.

9. In a circular knitting machine, the combination with the cam cylinder and needle cylinder, of driving connections to one of the cylinders, control mechanism, rotary

- mechanism and oscillatory mechanism, shifting means governed by the control mechanism to connect the driving connections alternately with the rotary mechanism and 5 oscillatory mechanism, a ratchet having a number of teeth, a pawl adapted to actuate the ratchet when the latter is turned into a certain position, a driving shaft, means actuated thereby to operate the rotary and oscillatory mechanism, the control mechanism and the pawl; a cam actuated by the control mechanism, a lever operable by said cam, a link operable by said lever, a pawl on the link adapted to engage said ratchet and turn 10 the same after a predetermined rotation of the control shaft into operative relation with the first-named pawl, mechanism to stop the rotation of the driving shaft, and means controlled by the ratchet wheel to operate 15 the stop mechanism.
10. In a circular knitting machine, the combination with the cam cylinder and needle cylinder, of mechanism for moving one of said cylinders vertically, control 20 mechanism, the driving shaft, means actuated by the driving shaft to drive the control 25

mechanism, pattern mechanism, means controlled by the pattern mechanism to control the operation of the control mechanism, a cam turning with the control mechanism 30 adapted to operate said cylinder-lifting mechanism, driving connections to the other cylinder, rotary mechanism and oscillatory mechanism, means governed by the control mechanism to connect the driving connections alternately with the rotary mechanism and the oscillatory mechanism, a driving shaft, mechanism to stop the rotation of the driving shaft, means controlled by the control mechanism to effect the operation of 35 the stop mechanism, mechanism actuated by the driving shaft to actuate the last named means, and devices actuated by the last named means to operate the cylinder lifting mechanism. 40

In testimony of which invention, I have hereunto set my hand, at Phila., on this 25th day of October, 1912.

HARRY A. HOUSEMAN.
